UNITED STATES PATENT OFFICE.

QUINTO GAVAZZI, OF OLD FORGE, PENNSYLVANIA.

MINE-GATE LOCK.

1,188,752.

Specification of Letters Patent. Patented June 27, 1916.

Application filed March 31, 1915. Serial No. 18,839.

To all whom it may concern:

Be it known that I, QUINTO GAVAZZI, a citizen of the United States of America, and resident of Old Forge, in the county of 5 Lackawanna and State of Pennsylvania, have invented certain new and useful Improvements in Mine-Gate Locks, of which the following is a specification.

This invention relates to mine cars and 10 particularly to safety devices for the doors thereof, the said invention having for its object the provision of novel means for locking the door and retaining it locked until such time as the car is in position at the 15 landing for receiving or discharging a load, novel means being provided whereby the car or device carried thereby actuates a lock or latch releasing device so that the latch is free to be moved out of engagement with 20 its interlocking member only when the car is opposite the said landing or door.

A still further object of this invention is 25 to provide novel means for returning the latch guard to its normal operative position when the car has been moved out of engagement with the guard operating means.

With the foregoing and other objects in view, the invention consists in the details of construction, and in the arrangement and 30 combination of parts to be hereinafter more fully set forth and claimed.

In describing the invention in detail, reference will be had to the accompanying drawings forming part of this specification 35 wherein like characters denote corresponding parts in the several views, and in which—

Figure 1 illustrates a fragment of an elevator shaft showing the door in section 40 and the locking mechanism associated therewith; Fig. 2 illustrates a horizontal sectional view thereof showing a fragment of the car; Fig. 3 illustrates a perspective view of the latch; Fig. 4 illustrates a side elevation thereof with the latch operating lever in section; Fig. 5 illustrates a plan view of the latch and latch engaging member; and Fig. 6 illustrates a plan view of the latch 45 engaging member.

In these drawings 7 denotes a guide rail 50 usually employed in elevators, 8 a channel iron constituting a part of an elevator car which operates in conjunction with the guide rail, although the means for guiding the car and the means coacting with the said guiding means may be of any appropriate

construction and I do not wish to be limited with respect to the construction of the elevator, as it will be apparent from an inspection of the invention that the guard for the door latch may be actuated from any part of the car, so long as the car is provided with a tripping device, a type of which is shown herein and is identified by the reference numeral 9. In the present embodiment of 60 this feature of the invention, a wheel is employed which is carried by the car and the said wheel is adapted to operate toggle levers 10 for forcing them inwardly; the said toggle levers being operated in an opposite direction by a spring 11 connected to a pivot 12 of the toggles, the opposite end of the spring being anchored to an arm 13 extending from the plate 14, the said plate having a stud 15 on which the lower ends of the 65 toggle levers are pivoted. The plate is secured to the well casing 16 in any appropriate way.

As a means for limiting the movement of the toggles under the influence of the spring, 70 the said spring is housed in a tube 17 with a flared end 18 against which the toggles abut and the said tube is interposed between the toggles and the arm as shown in Fig. 1. A bar 19 is pivotally connected to the ends 75 of the toggles remote from the pivot on the plate and the said bar is pivotally connected to a bell crank 20, which bell crank is mounted on a pivot 21. The bell crank 20 operates a thrust bar 22 and the thrust bar in turn is 80 pivotally connected to a guard 23, which guard is slidable on a plate 24 secured to the inner wall of the well casing. The plate 24 has a downwardly extending spring 85 tongue 25 with an aperture 26 and the said plate 24 has a guide 27 through which the guard is slidable.

The door 28 of the well casing has a housing 29 secured to it and the said housing carries a pivot 30 on which the latch 31 90 is mounted, there being spacing collars 32 on the pivot 30 between the latch and the sides of the housing. Furthermore, the said housing has a pin 33 extending therethrough 95 which constitutes a support for the latch. From the fact that the door carries a housing and latch, the said latch rides over the curved surface of the tongue 25 when the door is closed and the nose 34 of the latch 100 will drop into the aperture 26 of the tongue, thus effecting an interlocking engagement 105 which will prevent opening of the door un-

til the latch is elevated clear of the tongue. To prevent accidental movement of the latch after it has engaged the tongue of the plate, the guard 23 is caused to overlie the 5 latch and engage a lug 35 which is formed thereon to maintain the interlocked relation of the latch and tongue. In order to disengage the latch and tongue after the guard is removed from the latch, a lever 10 36 is pivoted to the door and one end thereof projects through an aperture 37 in the housing and under the latch so that when the upper end of the lever is operated, the latch will be elevated from engagement with 15 the tongue and the door may swing open.

From what has been said of the guard operating mechanism, it is apparent that the latches of all the doors of a mine shaft are guarded at all times except when the 20 car is stopped at a landing where it is unguarded, and furthermore, that the car must be in a certain position with relation to the landing before the latch is unguarded. The relation of parts can, therefore, be maintained so that the operator of a mine car 25 cannot open the door when the car is above or below the landing, or when the car is in motion. The tongue 25 is resilient and the nose of the latch has a curved surface 30 constituting a cam which rides over the tongue, thus elevating the latch so that it will fall into the aperture or slot of the tongue.

Copies of this patent may be obtained for five cents each, by addressing the "Commissioner of Patents, Washington, D. C."

I claim—

1. In a mine door lock, a plate having a 35 tongue, said plate being stationary with relation to a door of a mine cage, a housing secured to the door and adapted to swing therewith, a latch carried by the housing and adapted to interlock with the tongue of 40 the plate, a guard adapted to slide into engagement with the latch and retain the same in engagement with the tongue, a toggle, means for connecting the toggle to operate the guard, and means carried by a mine 45 car for operating the toggle.

2. In a mine door lock, a plate having a depending apertured tongue stationary with relation to the door of a mine cage, a housing carried by the door, a latch member 50 pivotally supported by the housing, a guard member carried by the plate, a guard operating in the guard member, toggle levers associated with the guard, means for normally holding the guard into engagement 55 with the latch member, and means carried by a mine cage for engaging the toggle and moving the guard out of engagement with the latch.

In testimony whereof, I affix my signature in the presence of two witnesses.

QUINTO GAVAZZI.
